UNITED STATES PATENT OFFICE.

CARLETON W. NASON, OF MONTCLAIR, NEW JERSEY, ASSIGNOR TO THE
NASON MANUFACTURING COMPANY, OF NEW YORK, N. Y.

DESIGN FOR A FOOT-RAIL BRACKET.

SPECIFICATION forming part of Design No. 13,182, dated August 15, 1882.

Application filed July 19, 1882. Term of patent 14 years.

To all whom it may concern:

Be it known that I, CARLETON W. NASON, of Montclair, in the county of Essex and State of New Jersey, have invented a new and Improved Design for Foot-Rail Brackets, of which the following is a full, clear, and exact description.

The drawing is a perspective view of my newly-designed foot-rail bracket.

The leading feature of my improved design consists in the figure of a griffin bearing a ring upon its forehead. The griffin is represented in a sitting position with its body A curved forward, upward, and backward, and with the back of its neck resting upon the top of its wings B, which project backward and upward. The lower part, C, of the wings is represented as extending forward and downward, so as to rest upon the ground in front of the body A. The tail D is represented as being curved upward and forward, so as to rest upon the back

of the body A. The lower legs, E, are represented as formed together, and as resting upon the ground. The upper legs, F, are represented as formed together, and as projecting forward. Upon the forehead of the griffin rests the rail ring or socket G.

Having thus described my invention, I claim as new and desire to secure by Letters Patent—

The design for a foot-rail bracket, herein shown and described, the same consisting of the figure of a griffin having its body curved forward, upward, and backward, having its wings extended upward and backward, and with their lower part extended forward and downward to rest upon the ground, and having a rail-ring upon its forehead.

CARLETON W. NASON.
